UNITED STATES PATENT OFFICE.

WILLARD T. CASE, OF NEW BRUNSWICK, NEW JERSEY, ASSIGNOR TO DELTOX GRASS BUG COMPANY, OF OSHKOSH, WISCONSIN, A CORPORATION OF WISCONSIN.

DESIGN FOR A GRASS MAT.

55,933.

Specification for Design.

Patented Aug. 3, 1920.

Application filed October 17, 1919. Serial No. 331,477. Term of patent 7 years.

To all whom it may concern:

Be it known that I, WILLARD T. CASE, a citizen of the United States, residing at New Brunswick, in the county of Middlesex and State of New Jersey, have invented a new, original, and ornamental Design for a Grass Mat, of which the following is a description, reference being had to the accompanying drawing, forming part thereof.

The drawing is a plan view of a grass rug showing my new design.

I claim:

The ornamental design for a grass mat, as shown.

WILLARD T. CASE.
